UNITED STATES PATENT OFFICE

1,987,003

DUPLEX STEAM ENGINE

Myron W. Dole, Belmont, Mass.

Application July 13, 1934, Serial No. 734,999

14 Claims. (Cl. 121—115)

This invention relates to duplex steam engines of the type in which the pistons have no mechanical connection with each other and are, therefore, capable of movement independently of each other, and in which the piston-reversing means is constructed to maintain the pistons in an out-of-step relation so that they will not reverse at the same time. A steam engine of this type is illustrated in my Patent No. 1,962,986, 5 June 12, 1934. Such a duplex steam engine is useful for various purposes, such as operating a duplex double-acting pump so as to produce a continuous flow, the out-of-step relation between the pistons resulting in each piston delivering fluid through the discharge of the pump while the other piston is reversing.

In the device shown in my above-mentioned patent one of the power pistons is a self-reversing piston, the valve mechanism for the corresponding cylinder being of the usual type which causes piston reversal at each end of the stroke automatically by the movement of that piston. The valve mechanism for the other cylinder is constructed so that it causes piston reversal automatically by the operation of its piston at one end of the stroke while at the other end of the stroke the joint action of said piston and a valve mechanism controlled by the other or first-named or self-reversing piston is necessary to cause piston reversal.

One of the objects of the present invention is to provide improvements in valve mechanism for steam engines of this type by which the devices rendered operative by the self-reversing piston 35 to assist in reversing the other piston at one end of its stroke will be operative during a limited portion only of the stroke of said self-reversing piston and will be inoperative at other portions of the stroke. In other words, the construction 40 of this invention is such that during a limited portion of the stroke of the self-reversing piston the latter provides the opportunity for the reversal of the other piston provided it has reached the end of its stroke, such opportunity being removed after the self-reversing piston has completed its travel through the predetermined portion of its stroke.

The valve mechanism illustrated in said patent is of the type in which the steam valve for each 50 cylinder is actuated by a differential piston mechanism arranged so that when steam is admitted to one end of the cylinder of the differential piston said valve will be shifted into one position to admit steam to one end and to exhaust steam from the other end of the power

cylinder, while when steam is exhausted from said end of the differential cylinder the differential piston operates to shift the valve into position to admit steam to the other end and to exhaust steam from the first-named end of the power cylinder, and admission and exhaust of steam to the end of the differential cylinder is determined by a reversing valve which is actuated from the power piston.

In the operation of steam engines of this type 10 it is desirable that each power piston should make the full complete stroke and in order that the stroke of each power piston may be completed in one direction it is necessary that the steam pressure should be maintained in one end of the differential cylinder for the steam valve during the entire stroke of said power piston.

Another object of my present invention is to provide improvements which will ensure the maintenance of the proper steam pressure in the differential cylinder to prevent the valve from reversing even though there should be leakage of steam from the differential cylinder, this feature constituting, as it were, a steam-pressure-maintaining feature for preventing reversal of the steam valve until the power piston has completed its stroke.

My present invention is adapted for use in a duplex engine whether the latter be of the simple type or the compound type and for illustrative 30 purposes I have shown in the drawings the invention as applied to both types of engines.

Fig. 1 is a diagrammatic sectional view of a duplex steam engine having simple cylinders and showing a selected embodiment of my invention; 35

Fig. 2 is a sectional view of the valve device which co-operates with one of the pistons to effect the reversal of the other piston at one end of its stroke;

Fig. 3 is a view similar to Fig. 1 but showing one way in which the invention may be applied to a compound engine;

Fig. 4 is a view similar to Fig. 2 but showing the type of valve and its connections used with the compound engine.

Fig. 5 is a fragmentary view looking toward the left in Fig. 2 and showing the check valves 58.

In the selected embodiment shown in Fig. 1 the duplex steam engine comprises the two cylinders 1 and 2 in which operate the power pistons 3 and 4. Each piston has the usual piston rods 5, and if the engine is used to operate a pump these piston rods will be connected to the pump pistons of the duplex pump as usual in devices of this type.

The valve mechanism controlling the admission of steam to the cylinder 1 is of known construction and is such as is commonly used in steam engines of this type. The steam valve for the cylinder 1 is shown at 6 and it operates in a steam chest 7 which communicates by a passage 8 with a steam supply pipe 9. The cylinder 1 is provided with the two ports 10 and 11 leading from the steam chest 7 to the opposite ends of the cylinder 1 and the valve 6 has the usual exhaust cavity 12 which, when the valve 6 is in the position to uncover the port 10 for admission of live steam, connects the port 11 with the exhaust port 13 leading to the exhaust pipe 14, while when the valve is shifted into its other position to uncover the port 11 for the admission of live steam, said cavity 12 connects the port 10 with the exhaust port 13.

The valve 6 is of the usual steam-actuated type, it being connected to and operated by a differential piston structure comprising the two piston elements 15, 16. The action of the steam pressure in the steam chest 7 on the differential piston normally tends to move the differential piston into its right hand position thereby connecting the port 10 with the exhaust and admitting steam to the port 11, in which case the power piston 3 would be moved upwardly.

To bring the valve 6 into the position shown in Fig. 1 live steam is admitted to the cylinder space 17 at the right hand side of the larger piston element 16 thereby substantially balancing the pressure against the left hand side of said piston element, the result being that the pressure of the steam against the smaller piston element 15 will shift the valve into the position shown in Fig. 1 thereby admitting steam to the upper end of the cylinder 1. The control of the admission of steam to the chamber 17 is through the usual reversing valve 18 which is actuated by the piston 3. This reversing valve operates in a steam chest 19 which is supplied with live steam through the steam passage 20. When the reversing valve is in its raised position the cylinder space 17 has communication with the steam chest 19 through the port 21, the admission of steam to the cylinder space 17 causing the differential piston 15, 16 and valve 6 to take the position shown in Fig. 1. When the reversing valve 18 is in its lowered position the inlet port 21 is closed and the cylinder space 17 is connected with the exhaust port 13 through the ports 22, 23 and the exhaust cavity 24.

The valve 18 is reversed in the usual way by the movement of the power piston 3 through the medium of the reversing plate 25 which co-operates with the reversing rod 26 secured to the valve 18, said reversing rod extending into an axial recess formed in the piston rod 5 and having the shoulders 27, 28 thereon with which the plate 25 engages near the ends of the stroke of the power piston 3. As the power piston 3 nears the lower end of its stroke the reversing plate 25 engages the shoulder 28 and draws the valve 18 downwardly thereby causing exhaustion of the live steam from the cylinder space 17 so that the differential piston 15, 16 will shift the valve 6 to the right, thus reversing the power piston 3. Just before said power piston 3 reaches the upper end of its stroke the reversing plate 25 engages the shoulder 27 and returns the reversing valve to the position shown in Fig. 1 thereby again admitting live steam to the cylinder space 17 and causing the differential pistons 15, 16 to shift

into the position shown in the drawing which will again reverse the power piston 3.

As stated above this type of valve mechanism is such as is commonly employed in certain types of steam engines and is one which admits live steam to the cylinder during the entire stroke of the power piston, and in which cut-off comes at the end of the stroke and there is no expansion of steam. This arrangement has the advantage that it ensures that the piston will always start when supplied with live steam, for with the cut-off at the end of the stroke the port leading to one or the other end of the cylinder will always be open when steam is again admitted, regardless of the position in which the power piston may be when the engine stops.

It will be noted that with this valve mechanism the movement of the steam valve in one direction is accomplished by admission of live steam to the cylinder space 17 and the movement in the opposite direction is accomplished by exhausting the steam from said cylinder space 17.

The admission of steam to the steam cylinder 2 is controlled by a steam valve 29 which is similar in all respects to the valve 6, said valve operating in a steam chest 30 which communicates with the passage 8 and said steam cylinder 2 having the ports 31 and 32 leading from the steam chest 30 to the opposite ends thereof.

33 is an exhaust port which is brought into communication with either of the ports 31 or 32 through an exhaust cavity 94 of the valve 29 depending upon the position of the valve. This valve 29 is also a steam operated valve and it has associated therewith the differential piston mechanism comprising the piston elements 34 and 35, the latter being larger than the former. The valve 29 is shown in Fig. 1 in position to admit steam to the lower end of the cylinder 2 and to connect the upper end of the cylinder to the exhaust port 33, as a result of which the piston 4 will be moving upwardly. The valve 29 is shifted to the left to reverse the power piston 4 by admitting steam to the cylinder space at the right hand end of the piston element 35. The admission of steam to this end is controlled by the reversing valve 36 which is similar in construction to the reversing valve 18, said valve having the reversing rod 37 thereon which extends into an axial bore in the piston rod 5 and is actuated to reverse the valve 36 by the reversing plate 38 which is secured to the power piston 4 and which engages the shoulders 39 and 40 on the reversing rod 37 as the piston 4 nears each end of its stroke.

The power piston 4 will reverse itself at the lower end of its stroke for when said piston reaches the lower end of the stroke the reversing plate 38 will engage the shoulder 40 and will draw the reversing valve 36 downwardly into the position shown in Fig. 1. This will cut off the inlet port 41 and will connect the port 42 with the exhaust port 43 through the exhaust cavity 44. When the reversing valve is in this position the pressure of the live steam in the steam chest 30 on the differential pistons 34, 35 holds said pistons and the valve 29 in the position shown in Fig. 1.

When the power piston 4 reaches the upper end of its stroke it shifts the reversing valve 36 upwardly to uncover the inlet port 41. In order to effect the reversal of the power piston 4, however, it is necessary to admit live steam to the cylinder space at the right of the differential piston element 35 and the admission of such live

steam is controlled by the movement of the power piston 3.

Live steam is admitted to the steam chest 66 for the valve 36 through a passage 45 and pipe connection 46 which leads to a valve device 47. This valve device has a cylinder chamber in which operate two piston valves 48 and 49 of different diameters. The piston valve 48 is provided with a stem 100 which enters an axial recess 101 formed 10 in the piston valve 49 and which is provided with a shoulder 102 which has engagement with the piston valve 49. With this construction when steam is admitted either beneath the piston valve 48 or above the piston valve 49, the two piston valves will move as a unit, but if steam pressure is admitted to the space 67 between the piston valves then they are permitted to separate, the reason for which will be more fully hereinafter set forth.

20 The valve casing is provided with an inlet port 50 communicating with an inlet pipe 51, said pipe 51 having two branches 52 and 53 that lead to the cylinder 1, the branch 52 communicating with the cylinder at the port 54 near the upper 25 end thereof and the pipe 53 communicating with the cylinder at the port 55 near the lower end thereof. The upper end of the cylinder chamber of the valve casing 47 is connected by a pipe 56 to a port 57 leading into the cylinder 1 approximately midway of the length thereof. The pipe connections 52 and 53 each have a check valve 58 therein, each check valve permitting free flow of steam through its pipe connection to the inlet pipe 51 but preventing flow in the opposite direction.

As the power piston 3 moves downwardly and uncovers the port 54 live steam will be admitted to the pipe connection 52 and through the inlet pipe 51 and port 50 to the lower end of the cylinder chamber in the valve casing 47, the check valve 58 in the pipe connection 53 preventing flow of steam from the pipe connection 52 to the pipe connection 53. At this time the ports 57 and 55 are on the exhaust side of the power piston 3. 40 The admission of the live steam through the pipe connection 52 will operate to raise the piston valves 48, 49 thereby uncovering the port 59 and allowing the live steam supplied through the pipe connections 52 to flow through the pipe connection 46 and passage 45 into the steam chest 66 of the reversing valve 36.

The same thing occurs when the power piston 3 is moving upwardly and has uncovered the port 55, the live steam then being admitted to the piston valve and to the connection 46 and passage 45 through the pipe connection 53, the check valve 58 in the pipe connection 52 preventing flow of steam from pipe connection 53 to pipe connection 52. These check valves 58 thus prevent bypassing of steam through either pipe connection 52, 53 when steam is admitted through the other connection.

It will be understood that the power piston 4 reverses itself automatically when it reaches the bottom of its stroke. When said power piston 4 nears the upper end of its stroke it raises the reversing valve 36 but there will be no shifting of the steam valve 29 until the power piston 3 reaches a predetermined position, which may either be that in which it uncovers the port 54 on the downward stroke or uncovers the port 55 on the upward stroke, thus admitting live steam to the uncovered port. As soon as this happens then the differential piston valve 48, 49 will be actuated as above described and live steam will

be admitted to the steam chest of the valve 36 thereby to operate the differential piston 34, 35 and thus reverse the power piston 4. The power piston 3, therefore, provides during each stroke thereof an opportunity for reversing the valve 29 provided the power piston 4 has previously reached the upper end of its stroke and has raised the reversing valve 36. The construction of the valve mechanism 47, however, is such that this opportunity will be removed after the power piston 3 has moved through a predetermined portion of its stroke and if the reversal of the piston 4 does not occur while this opportunity lasts then said piston 4 cannot be reversed until the piston 3 offers another opportunity for such reversal. 10 This opportunity for reversing the power piston 4 at the upper end of its stroke occurs while the power piston 3 is moving from either the port 54 or the port 55 to the port 57. Assuming that the power piston 3 is moving downwardly, then when 20 it uncovers the port 54 the differential piston valve 48, 49 is shifted as above described to allow steam to be admitted to the steam chest of the valve 36 thereby giving the opportunity for reversal of the valve 29 provided the power piston 25 4 has reached the upper end of its stroke.

When the power piston 3 has moved downwardly far enough to uncover the port 57 then live steam will be admitted through the pipe connection 56 to the upper end of the cylinder chamber in the piston valve casing 47. Since the upper piston member 49 is larger than the piston member 48 the admission of steam to the upper end of the cylinder chamber will force the differential piston downwardly into the position shown in Fig. 2 and in this position the port 59 with which the pipe connection 46 communicates will be in communication with a port 60 leading to a pipe connection 61 that leads to the steam space 62 at the upper end of the cylinder 2.

The operation of the device is as follows. Suppose the engine to be just starting from rest. The power pistons 3 and 4 may be in any position and may start in either direction when steam is first turned on. Assuming, for example, that the power piston 3 has just been reversed at the upper end of its stroke then when the steam is turned on the steam valve 6 will be in the position shown in Fig. 1 and steam will be admitted to the upper end of the cylinder 1 so that the power piston 3 is moving downwardly. If the power piston 4 and its valve are positioned so that said piston starts to move downwardly then it will reverse itself at the bottom end of its stroke and start upwardly. When the power piston 4 nears the top of its stroke it raises the reversing valve 36 thus uncovering the port 41 and the parts must remain in this position until live steam has been admitted to the steam chest of the valve 36 through the movement of the power piston 3. 50 As soon as the piston 3 uncovers either the port 54 when moving downwardly or the port 55 when moving upwardly the differential valve 48, 49 will operate to admit steam to said steam chest 66 of the valve 36 and thus cause reversal of the valve 29.

If, however, the power piston 4 has not reached the upper end of its stroke and raised the reversing valve 36 before the power piston 3 passes the port 57 then the opportunity for reversal of the power piston 4 is removed, for when the power piston 3 over-travels the port 57 then live steam is admitted through the pipe connection 56 into the upper end of the piston valve chamber 47 and both differential pistons

48, 49 move downwardly thus cutting off the supply of live steam to the steam chest 66 of the valve 36 through the pipe connection 46. If after this occurs the power piston 4 reaches the upper end of its stroke and is ready to reverse there will be no steam to cause reversal of the valve 29 and said power piston 4 must, therefore, wait in its raised position until live steam is again admitted to the steam chest of the valve 36.

10 As soon as the differential piston valves 48, 49 have been moved downwardly into the position shown in Fig. 2 the steam chest of the valve 36 has communication with the clearance space 62 at the upper end of the cylinder 2 through the 15 passage 45 and pipe connection 46, port 59, port 60 and pipe connection 61, the two ports 59 and 60 being in communication as shown in Fig. 2. The steam pressure, which was built up in the steam chest 66 when the power piston 3 over-travels the port 54, will thus be exhausted thus 20 removing the opportunity for reversing the valve 29.

From the above it will be seen that an opportunity is given the power piston 4 to reverse 25 while the power piston 3 moves downwardly from the port 54 to the port 57 and that the opportunity is removed as soon as said power piston 3 passes by the port 57. It will also be seen that another opportunity for the power piston 4 to 30 reverse is again presented while the power piston 3 is moving upwardly from the port 55 to the port 57 and that when said power piston is moved upwardly beyond the port 57 such opportunity is again removed.

35 The opportunity, therefore, for the power piston 4 to reverse at the upper end of its stroke is given after the power piston 3 leaves either end of its stroke and while it is moving from near either end to about the center of the cylinder 1, and hence under normal conditions the reversing of the power piston 4 at the upper end of the 40 stroke must occur while the piston 3 is moving through a predetermined portion of its stroke in one or the other direction.

45 The construction above described not only provides for the reversal of the power piston 4 at the upper end of its stroke but it ensures that the power piston 4 will make its complete downward stroke before again reversing. In order to 50 secure this result it is necessary that the valve 29 should be maintained in its left hand position during the entire downward stroke of the power piston. If it be assumed that the power piston 4 has reversed at the upper end of its stroke before the power piston 3 has uncovered the port 57 then as soon as said port has been 55 uncovered the differential piston valves 48, 49 will be moved into the position shown in Fig. 2. This will place the pipe connections 61 and 46 in communication so that live steam which is being admitted to the upper end of the cylinder 2 may pass through the connections 61, 46 and into the steam chest 66 thereby maintaining the necessary pressure therein to hold the valve 29 in its 60 left hand position and avoiding the possibility that such pressure might be lost due to leakage or otherwise before the power piston 4 has completed its downward stroke, which loss of pressure would result in the valve 29 being moved into the position shown in Fig. 1 and thus reversing the power piston 4 before it had completed its downward stroke.

When the live steam is passing through the pipe connection 61 into the steam space 67 of the differential valve the steam pressure on the

under face of the piston valve 49 tends to raise it but as the piston valve 49 is separate from the piston valve 48 this steam pressure merely raises the piston valve 49 and holds the piston 48 in its lowered position and the communication between the ports 59 and 60 is thus preserved. This piston valve structure, therefore, also functions as a pressure-maintaining means for maintaining the pressure in the steam chest 66 during the entire downward stroke of the power piston 4. 10

My invention as disclosed in Fig. 1, therefore, provides means for positively causing the power pistons 3 and 4 to assume definite positions relative to, but out of step with, each other when steam is first turned on, and to maintain these 15 positions during the operation regardless of the relative speeds of the pistons, such relative positions of the pistons being determined by the position of the ports 54, 55 and 57. With this improvement, therefore, it is impossible for the 20 two power pistons to reverse simultaneously and they are always maintained in out-of-step relation. The invention also provides means whereby the power piston 4 is given an opportunity for a short interval of time only during each stroke 25 of the power piston 3 to reverse and to get into the predetermined out-of-step relation with said power piston 3.

The invention further ensures that each piston will make a full stroke in either direction 30 before reversing and it prevents any undesired reversal of the power piston 4 during its downward stroke by providing a pressure-maintaining feature for maintaining the pressure in the chamber 66 during the full downward stroke of 35 said power piston 4.

In Fig. 3 I have illustrated my invention as it might be applied to a duplex engine in which the cylinders are compounded. In said figure 71 represents the high pressure cylinder having the 40 high pressure piston 72 therein and 73 is the low pressure cylinder having the low pressure piston 74 therein.

The valve mechanism for controlling the supply of live steam to the high pressure cylinder 71 45 is similar to that above described for supplying steam to the cylinder 1 in Fig. 1 and comprises a steam valve 6 operating in a steam chest 7 and controlled by two differential pistons 15, 16, the operation of which in turn is controlled by the 50 reversing valve 18 that is actuated by the reversing plate 25 carried by the piston 72.

The valve mechanism controlling the admission of steam to the low pressure cylinder 73 is also the same as that shown in Fig. 1 for controlling 55 the supply of steam to the cylinder 2 and comprises a steam valve 29 operating in a steam chest 30 and operated by differential pistons 34, 35, the operation of which in turn is controlled by a reversing valve 36, the position of which is reversed 60 at each end of the stroke of the low pressure piston through the operation of a reversing plate 38 and reversing rod 37.

Since Fig. 3 shows a compound engine the live steam will be admitted to the steam chest 7 only 65 and the steam chest 30 is connected through a passage 75 to a receiver chamber 76 into which the steam from the high pressure cylinder 71 is exhausted as shown in the above-mentioned Patent No. 1,962,986. The live steam for the high 70 pressure cylinder is supplied through a supply pipe 77 which communicates with the steam chest 7 through the passage 78.

The differential valve mechanism which is controlled by the high pressure piston 72 and which 75

cooperates with the low pressure piston 74 to ensure reversal of the latter at the upper end of the stroke is shown in section in Fig. 4 and it comprises a valve casing 79 in which operates two differential piston valve members 80, 81 which are similar to the piston valve members 48, 49. The high pressure cylinder 71 has the port 82 which is connected by a pipe connection 83 to the port 84 near the lower end of the valve casing 79. Said high pressure cylinder has another port 85 communicating by a pipe connection 86 with a port 87 near the upper end of the piston valve casing 79. The steam chest 66 in which the valve 36 operates is connected by a pipe connection 88 to a port 89 leading to the cylinder chamber of the piston valve structure 79. This piston valve structure has another port 90 corresponding to the port 60 of Fig. 2 and which communicates with a pipe connection 91 to the clearance space 92 at the upper end of the low pressure cylinder 73.

In the operation of the compound engine shown in Fig. 3 if it be assumed that the high pressure piston 72 is moving downwardly and the low pressure piston moving upwardly as shown by the arrows, then when the high pressure piston 72 moves downwardly past the port 82, live steam will be admitted to the lower end of the valve casing 79 through the pipe connection 83 thereby raising the differential piston valve 80, 81 so as to place the ports 84, 89 in communication. This will allow the live steam to flow through the pipe connection 88 into the reversing valve chamber 66. If at this time the low pressure piston 74 has reached the upper end of its stroke then it will have raised the reversing valve 36 by the action of the reversing plate 38. The raising of the reversing valve into its upper position will uncover the port 41 so that the live steam from the reversing valve chamber 66 may be delivered to the chamber containing the differential pistons 34, 35. This will shift the differential pistons to the left thereby causing reversal of the low pressure piston. The construction, therefore, is similar to that shown in Fig. 1 in that during a predetermined portion of the travel of the high pressure piston 72 it provides the opportunity for the reversal of the low pressure piston provided said low pressure piston has reached the upper end of its stroke.

As the high pressure piston continues its downward movement and uncovers the port 85 then live steam will be admitted through the pipe connection 86 to the upper end of the valve casing 79 and because of the differential nature of the piston valves 80, 81 said piston valves will be forced downwardly into the position shown in Fig. 4.

If the low pressure piston 74 has reached the upper end of its stroke and raised the reversing valve 36 prior to the overrunning of the port 85 by the high pressure piston 72 then when the differential piston valve 80, 81 has been moved into the position shown in Fig. 4 the pipe connections 88 and 91 will be brought into communication and steam under receiver pressure will flow through the pipe connections 91, 88 so as to maintain the receiver pressure in the reversing-valve chamber 66, such receiver pressure maintaining the differential piston 34, 35 in its left hand position during the full downward stroke of the low pressure piston 74. If, however, the low pressure piston has not reached the upper end of its stroke and, therefore, has not raised the reversing valve 36 before the high pressure piston 72 overruns the port 85, then the bringing of the pipe connections 88 and 91 into communica-

cation by the shifting of the differential piston valve 80, 81 into the position shown in Fig. 4, will connect the reversing-valve chamber 66 with the exhaust through the pipe connections 88, 91 and the receiver pressure which was admitted to the reversing-valve chamber will be exhausted thereby removing the opportunity for the reversal of the low pressure piston. 5

The apparatus shown in Fig. 3, therefore, operates as described with reference to Fig. 1 in that during a predetermined portion of the travel of the high pressure piston it provides the opportunity for the reversal of the low pressure piston, and if such reversal does not take place during the movement of the high pressure piston through such predetermined portion of its travel, then the opportunity is taken away and the low pressure piston cannot be reversed until the high pressure piston again provides such opportunity for reversal during a succeeding stroke. The particular portion of the stroke of the high pressure piston during which such opportunity for reversal of the low pressure piston is offered will depend upon the location of the ports 82, 85. 10 15 20

In the construction shown in Fig. 3 such opportunity for reversal of the low pressure piston will be presented during each down stroke only of the high pressure piston 72 but by providing the requisite number of ports and proper connections the opportunity for reversal might be offered during each stroke of the high pressure piston. 25 30

While I have illustrated herein two selected embodiments of my invention I wish it understood that the constructional features may be varied in many ways without departing from the invention as expressed in the appended claims. 35

I claim:

1. A duplex steam engine having two steam cylinders, a power piston in each cylinder, a valve for reversing one of the pistons, valve-operating means rendered operative jointly by said piston when it reaches one end of its stroke and by the movement of the other piston during its travel in either direction. 40 45

2. A duplex steam engine having two steam cylinders, a power piston in each cylinder, said pistons being capable of movement independently of each other and one of the pistons being a self-reversing piston, a valve for reversing the other piston, valve-operating means rendered operative jointly by said other piston when it reaches one end of its stroke and by the movement of the self-reversing piston during a predetermined portion of its travel in either direction for reversing said other piston at said end of the stroke, said valve-operating means being also rendered operative to reverse said other piston at the opposite end of its stroke solely by said other piston itself. 50 55

3. A duplex steam engine having two steam cylinders, a power piston in each cylinder, said pistons being capable of movement independently of each other and one of the pistons being a self-reversing piston, a valve for reversing the other piston, means rendered operative by the other piston as it reaches one end of its stroke to actuate said valve and means cooperating with the first-named means to cause the valve to be actuated jointly by said other piston when it reaches the opposite end of its stroke and by the movement of the self-reversing piston during a predetermined portion of its travel in either direction. 60 65 70

4. A duplex steam engine having two steam cylinders, a power piston in each cylinder, said pistons, being capable of movement independently 75

- of each other and one of said pistons being a self-reversing piston, a steam-actuated valve for reversing the other piston, means actuated by the other piston at one end of its stroke for rendering 5 said valve operative, and means controlled by the movement of the self-reversing piston during its travel in either direction and co-operating with said valve-actuating means to render the valve operative at the opposite end of the stroke 10 of said other piston.
5. A duplex steam engine having two steam cylinders, a power piston in each cylinder, said power pistons being capable of movement independently of each other and one of said power 15 pistons being a self-reversing piston, a steam-actuated valve for reversing the other piston at each end of its stroke, means rendered operative by said other piston at one end of its stroke to cause operation of said valve, and means co- 20 operating with said last-named means and controlled by the self-reversing piston during a predetermined portion only of its travel to render said valve-actuating means operative at the opposite end of the stroke of said other piston.
25. 6. A duplex steam engine having two steam cylinders, a power piston in each cylinder, said pistons being capable of movement independently of each other and one of said pistons being a self-reversing piston, a steam-actuated valve for 30 reversing the other piston at each end of its stroke, means rendered operative by said other piston at one end of its stroke to cause operation of said valve, and means co-operating with said last-named means and controlled by the self-revers- 35 ing piston during a predetermined portion only of its travel to admit steam to and thereby actuate said valve at the opposite end of the stroke of said other piston.
7. A duplex steam engine having two steam 40 cylinders, a power piston in each cylinder, said pistons being capable of movement independently of each other and one of said pistons being a self-reversing piston, a steam-actuated valve for reversing the other piston at each end of its 45 stroke, means rendered operative by said other piston at one end of its stroke to cause operation of said valve, and means co-operating with said last-named means and controlled by the self-reversing piston during a predetermined portion 50 only of its travel to admit steam to and thereby actuate said valve at the opposite end of the stroke of said other piston, and to exhaust the steam from said valve during another portion of the stroke of the self-reversing piston.
55. 8. A duplex steam engine having two steam cylinders, a power piston in each cylinder, said pistons being capable of movement independently of each other and one of the pistons being a self-reversing piston, a steam-actuated valve for re- 60 versing the other piston at each end of its stroke, a reversing valve for said steam-actuated valve, means to actuate the reversing valve by the movement of said other piston as it approaches each end of its stroke, and means co-operating 65 with said reversing valve and controlled by the self-reversing piston during a predetermined portion only of its travel in either direction to admit steam to said steam-actuated valve.
9. A duplex steam engine having two steam 70 cylinders, a power piston in each cylinder, said pistons being capable of movement independently of each other and one of the pistons being a self-reversing piston, a steam-actuated valve for reversing the other piston at each end of its 75 stroke, a reversing valve for said steam-actuated
- valve, means to actuate the reversing valve by the movement of said other piston as it approaches each end of its stroke, and means co-operating with said reversing valve and controlled by the self-reversing piston during a predetermined portion only of its travel in either direction to admit steam to said steam-actuated valve and to exhaust steam therefrom during another portion of the travel of said self-reversing piston. 5
10. A duplex steam engine having two steam 10 cylinders, a power piston in each cylinder, said pistons being capable of movement independently of each other and one of the pistons being a self-reversing piston, a steam-actuated valve for reversing the other piston at each end of its stroke, 15 a reversing valve controlling admission of steam to and its exhaust from said steam-actuated valve, means controlled by the self-reversing piston during a predetermined portion only of its travel to admit steam to the reversing valve and during 20 another portion of its travel in the same direction to exhaust steam therefrom, and means actuated by said other piston at each end of its stroke to reverse the position of the reversing valve. 25
11. A duplex steam engine having two steam 30 cylinders, a power piston in each cylinder, said power pistons being capable of movement independently of each other and one of the pistons being a self-reversing piston, a valve for reversing the other power piston at each end of its stroke, 35 a steam-actuated piston for operating said valve, a reversing valve controlling the delivery of steam to said piston for actuating the latter, means actuated by said other piston at each end of its stroke to reverse the position of the reversing valve, and means controlled by the self-reversing piston during a predetermined portion only of its travel to admit steam to the reversing valve, said last-named means being operative to maintain the steam pressure on the valve-actuating piston during the full stroke of said other power piston. 40
12. A duplex steam engine having two steam 45 cylinders, a power piston in each cylinder, said power pistons being capable of movement independently of each other and one of said pistons being a self-reversing piston, a valve for reversing the other power piston at each end of its stroke, 50 a steam-actuated piston for operating said valve, a reversing valve controlling the delivery of steam to said latter piston for actuating it, means actuated by said other power piston at each end of its stroke to reverse the position of the reversing valve, and means controlled by the self-reversing power piston during a predetermined portion only of its travel to admit steam to the reversing valve, 55 said last-named means being operative to maintain the steam pressure on the valve-actuating piston during the full stroke of said other power piston in case said other power piston has completed its stroke before the self-reversing piston 60 has completed the predetermined portion of its travel and to exhaust the steam from said reversing valve in case said other power piston is not reversed before the completion of said predetermined portion of the travel of the self-reversing piston. 65
13. A duplex steam engine having two steam cylinders, a power piston in each cylinder, a steam-actuated valve for reversing one of said pistons, means controlled partly by the other piston during a predetermined portion of its stroke and partly by the first-named piston for supplying steam to actuate said valve in case the first-named piston has reached the end of its stroke during the movement of said other piston through 70 75

said predetermined portion of its stroke, which means are inoperative to supply steam in case the first-named piston has not reached the end of its stroke while the said other piston is moving through said predetermined portion of its stroke.

- 5 14. A duplex steam engine having two steam cylinders, a power piston in each cylinder, said pistons being capable of movement independently of each other and one of said pistons being a self-reversing piston, a steam-actuated valve to reverse the other power piston, a reversing-valve chamber, means controlled by the self-reversing power piston to supply steam to the reversing-valve chamber during a predetermined portion of the stroke of said self-reversing power piston, and a reversing valve operating in said chamber

and actuated by said other power piston for controlling the admission of steam from said chamber to said steam-actuated valve, said means for supplying the steam operating to maintain the steam pressure in said chamber during the full stroke of said other power piston in case said other power piston reaches the end of its stroke during the travel of the self-reversing power piston through the predetermined portion of its stroke and to exhaust the steam from said chamber in case said other power piston does not reach the end of its stroke while the self-reversing piston is moving through said predetermined portion of its stroke.
